UNITED STATES PATENT OFFICE.

BASILE FRANÇOIS MAHÉ, OF CHARENTON, FRANCE.

MACHINE FOR GRINDING BALLS.

Application filed December 10, 1923. Serial No. 679,739.

To all whom it may concern:

Be it known that I, BASILE FRANÇOIS MAHÉ, engineer, a citizen of the Republic of France, residing at 18 Rue du Petit 5 Chateau, Charenton, Seine, France, have invented new and useful Improvements in Machines for Grinding Balls, of which the following is a specification.

The present invention relates to a machine 10 for grinding balls for ball bearings of the type in which two fixed vertical plates are arranged between two oppositely arranged grind-stones, which are carried by poppets mounted in slideways upon a frame, the 15 pressure necessary for the grinding of the balls, which are placed between the grind-stones and the plates, and pass alternately from one plate to the other at each revolution, being assured by the movement of the 20 grind-stones towards the plates under the action of a system of springs. In existing machines of this type, the spring pressure is exerted upon the poppets carrying the shafts of the grind-stones and tends to move these 25 latter towards the plates, which are rigidly fixed to the frame and the result is that the poppets cannot be fixed upon the frame, for the reason that they must be able to yield to the action of the spring. The result is 30 that the poppets are not firmly held upon their guide-ways, thereby giving rise to vibrations which are prejudicial to efficient operation of the machine and a further serious drawback arises in that the grit 35 arising from the grinding operation penetrates into the slideways and very soon damages them.

The present invention is intended to obviate this drawback and it is characterized 40 by the fact that the two plates can move axially in their support, which latter is fixed rigidly to the frame, adjustable springs being mounted between each of the plates and their support.

45 The invention is shown diagrammatically and by way of example in the accompanying drawings in which:

Fig. 1 is a elevation of the machine.

Fig. 2 is a section along II, II of Fig. 1.

50 Fig. 3 is a vertical axial section of the support for the plates.

Fig. 4 is a section along IV, IV, Fig. 5 and shows the device which serves to pass the balls from one plate to the other.

Fig. 5 is a plan view of this device with 55 portions in section.

Fig. 6 is a section along the line VI, VI, Fig. 1, showing the means for rotating the grindstones.

The machine consists of a frame 1, forming a receptacle and supporting, at each of its ends, two poppets 2, which can move in slideways and which carry the shafts of the grindstones 3. These latter rotate in the same direction and are driven by any 60 suitable transmission means from a stepped pulley 4 situated at the extremity of the machine. Said transmission means is shown as consisting of a shaft 21 to which is keyed the pulley 4, which shaft 21 drives two 65 transverse shafts 22 by means of bevel wheels 23 splined upon the shaft 21 which mesh with bevel wheels 24 keyed upon the shafts 22. A worm 25 is keyed to each of the shafts 22 and drives a worm wheel 26 70 keyed upon the shaft of the corresponding grindstone. The grindstones 3 may be rotated by hand, when necessary, by means of cranks mounted on the shafts 22, as will be explained below. In the centre of the 75 frame 1, there is rigidly fixed the holder 5 for the plates in which are mounted two plates 6, 6' having grooved faces and being located opposite the grind-stones 3.

As can be seen in Fig. 3, the plates 6, 6' 80 are mounted on hollow shafts 7, 7' which telescope one within the other and are supported by the plate-holder 5. Between the inner face of each plate and the plate-holder 5 there are arranged compression 85 springs 8, 8' having the same force. The shafts carrying the grind-stones are traversed by a screw threaded rod 9 which is rigidly fixed in one of the poppets, at one of its extremities, and which carries at its 90 other extremity a tapped handwheel 10 which bears against the other poppet. The rod 9 passes through the hollow shaft 7'.

The poppets 2 can be locked upon their slideways by means of locking devices 11. 100

The grooved plates 6, 6' are connected respectively to dynamometres 12, 12' which indicate the degree of compression of the springs 8, 8' when the machine is in operation.

105 The plates 6, 6' are both in two pieces, so as to enable their active grooved faces to be changed when necessary. The non-

removal portion of the plates is provided with a fork 13 (Fig. 2) which engages a shaft 14 rigidly fixed in the plate holder 5 and thereby prevents the plates from rotating during the operation of the machine.

I will now describe the device for transferring the balls from one plate to the other at each turn of the balls during the operation of the machine. This device is shown in detail in Figs. 4 and 5. This device connects the two plates 6, 6' at the front of the machine. It is constituted by an inclined plane 15 having a number of passages 16 which is equal to the number of grooves in the plates 6, 6'. These passages direct the balls from one groove of one of the plates into a groove of different diameter in the other plate, and the member 15 is inclined in such a manner that the balls descend by gravity from the left hand plate towards the right hand plate. The balls are caught on the plate 6' by a projection 17, and upon the plate 6 by a projection 18 which causes them to pass on to another inclined plane 19, which returns the balls to the plate 6'. This inclined plane 19 may or may not comprise a plurality of passages, in the same way as the inclined plane 15 but, if it is not provided with passages, the balls would pass haphazard into any groove of the plate 6'. The grindstones 3 revolve in the direction indicated by the arrows.

The method of operation is as follows: The locking devices 11 being released, and the poppets 2 being moved apart so as to leave, between the grindstones 3 and the grooved plate 6, 6', the necessary interval for the free passage of the balls in the grooves, the balls are introduced into the grooves by placing them upon the inclines 15 and 19 and the grindstones 3 are rotated by hand by means of cranks 20. When the grooves of the plates contain a sufficient number of balls, the machine is started and the handwheel 10 is operated so as to move the poppets 2 and grindstones 3 of the plates 6, 6' towards each other. The handwheel 10 is operated until the dynamometres 12, 12' indicate a pressure of approximately 3000 kilogrammes, whereupon the devices 11 are locked. The grindstones 3 are sprinkled with kerosene during the entire grinding operation. From time to time a ball is selected from one or the other of the inclines 15, 19 and is measured. When the desired dimension is approximately reached, that is to say, when the diameter is only from two to three hundredths of a millimetre more than the finished size, the pressure is reduced to 1000 kilogrammes by acting upon the handwheel 10. When finally, the balls have the desired dimension, the machine is stopped, the handwheel 10 is released as well as the locking devices 11 and the poppets 2 are moved apart, in such a

manner that the finished balls can escape easily from the plates 6, 6' and the grindstones 3, and fall into the receptacle of the frame 1.

It will be noticed that the mounting of the plates 6, 6' enables each of them to yield slightly under the action of irregularities of the balls, either by sliding axially or by yielding radially owing to the small amount of clearance which necessarily exists in the adjustment of the shafts 7, 7' in their bearings.

The invention is only described and shown by way of a merely explanatory example, which is not in any way limitative, and it is obvious that certain modifications could be made therein without thereby departing from the spirit of the invention as set forth in the following claims.

I claim:

1. A machine for grinding balls for ball-bearings, comprising grooved plates for receiving the balls, grindstones rotatably mounted opposite said plates, means for transferring the balls from one plate to the other, a support for said plates fixed to the frame, said plates being movable axially in their support and a spring interposed between each plate and its support.

2. A machine for grinding balls for ball-bearings comprising grooved plates for receiving the balls, grindstones rotatably mounted opposite said plates, means for transferring the balls from one plate to the other, a support for said plates fixed to the frame, said plates being movable axially in their support, a spring interposed between each plate and its support and means for regulating the pressure of said springs.

3. A machine for grinding balls for ball-bearings, comprising grooved plates for receiving the balls, grindstones rotatably mounted opposite said plates, means for transferring the balls from one plate to the other, a support for said plates fixed to the frame, hollow shafts carrying said plates and telescoping one within the other and in the support, a spring interposed between each plate and its support and means for regulating the pressure of said springs.

4. A machine for grinding balls for ball-bearings, comprising grooved plates for receiving the balls, grindstones rotatably mounted opposite said plates, means for transferring the balls from one plate to the other, a support for said plates fixed to the frame, a spring interposed between each plate and its support, means for varying the pressure of said springs and means for indicating said pressure.

5. A machine for grinding balls for ball-bearings, comprising grooved plates for receiving the balls, grindstones rotatably mounted opposite said plates, means for transferring the balls from one plate to the

other, a support for said plates fixed to the frame, a spring interposed between each plate and the support, a fixed shaft carried by said frame and engaging a notch in each of said plates.

6. A machine for grinding the balls of ball-bearings, comprising a frame, two poppets mounted on said frame and capable of being locked in position thereon, grindstones carried by said poppets, a support fixed on said frame, grooved plates carried by said support in proximity to said grind-

stones, means for transferring the balls from one plate to the other, a rod having one end connected to one of said poppets and passing through the other end of said rod being screw-threaded, said support and the other poppet, springs interposed between said support and said plates, and a hand-wheel engaging the screw-threads on said rod for altering the distance apart of said poppets and means for rotating said grindstones.

BASILE FRANÇOIS MAHÉ.
